CLAIM

The ornamental design for a fashion ornament as shown and described.

DESCRIPTION

FIG. 1 is a front perspective view of a fashion ornament in the environment of a shoe showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view of the fashion ornament in the environment of a shoe, with the fashion ornament in an alternative position.

The broken lines in the figures depict portions of the fashion ornament that form no part of the claimed design. The broken lines in the figures depicting the shoe environment form no part of the claimed design.

1 Claim, 8 Drawing Sheets
